(57) **CLAIM**

The ornamental design for a banknote handling machine, as shown and described.

DESCRIPTION

FIG. 1 is a front, top, right side perspective view of a banknote handling machine showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of portion A—A' thereof;

FIG. 9 is an enlarged view of portion B—B' thereof; and,

FIG. 10 is an enlarged view of portion C—C' thereof.

The broken lines shown in the drawings depict portions of the banknote handling machine that form no part of the claimed design.
